Primary Examiner — Mimosa De(74) Attorney, Agent, or Firm — Young Basile Hanlon & MacFarlane, P.C.(57) CLAIM

The ornamental design for a chair, as shown and described.

DESCRIPTION

FIG. 1 is a rear perspective view of a chair according to a first embodiment.

FIG. 2 is a front perspective view of the chair of FIG. 1.

FIG. 3 is a left-side perspective view of the chair of FIG. 1; and,

1 Claim, 4 Drawing Sheets(56)
